UNITED STATES PATENT OFFICE.

WILLIAM SAMPSON HORN, OF MILL GREEN, MARYLAND.

CORN-SILKING MACHINE.

SPECIFICATION forming part of Letters Patent No. 293,737, dated February 19, 1884.

Application filed October 15, 1883. (No model.)

To all whom it may concern:

Be it known that I, WILLIAM S. HORN, of Mill Green, in the county of Harford and State of Maryland, have invented a new and Improved Corn-Silking Machine, of which the following is a full, clear, and exact description.

This invention relates to a machine for removing the silk from green corn preparatory to canning; and it consists of the several combinations and constructions of parts, substantially as hereinafter fully set forth and claimed.

Reference is to be had to the accompanying drawings, forming part of this specification, in which the same letters of reference indicate corresponding parts in all the figures.

Figure 1 is a sectional elevation of my new corn-silking machine. Fig. 2 is a plan view of the same, and Fig. 3 is a detailed view of the slotted throat-plate of the hopper.

A represents the belt or apron, which is made endless and placed over the drums C C'; and B B represent the points or fingers of the apron A, which are made of pieces of wire or short rods of iron, secured at one end in the material of the belt or apron. The upper drum, C', is adapted to be revolved for giving a slow traveling movement to the apron or belt A. In this instance the drum C' is revolved by the belt D, that passes over pulley E on the feeder F, (which serves as the power-shaft of the machine,) and pulley G on the gudgeon of the drum C', and the drum C' is arranged in the frame H of the machine slightly back of the drum C, for giving the apron A a slight inclination, as shown clearly in Fig. 1, for properly receiving upon it the corn from the hopper J. The belt D also passes over the pulley K for revolving the brush L, which removes the silk from the fingers B B. The filaments of the brush L are secured to the shaft M (to which the pulley K is attached) by the removable clamp-plates a a, and the shaft M is flattened in the center, as shown in Fig. 1, so that the filaments or bristles will be properly held by the plates. By removing the plates a a the brushes, when worn, may be taken off and new ones supplied.

N is the front board of the machine, through which board the feed-opening b is made; and O O are the side boards, which partially in-

close the apron A, as shown. These side boards, O O, and the front board, N, are held in place in the frame H upon the rods P P, which pass through the frame, and the said boards are prevented from lateral movement upon the rods P P by the sleeves Q Q, placed upon the rods P P between the frame of the machine and the side boards, O O, as shown in Fig. 2.

Over the hopper-opening b is placed the slotted plate R. The above-mentioned feeder-shaft F passes in front of this plate R, and in this feeder-shaft are fitted the series of pins c c, which, when the feeder-shaft is revolved, pass through the slots e e of the plate R and serve to force the corn from the hopper J through the said slots, whence it will fall upon the apron A and fingers B, which latter will catch and retain the silk that is mingled with the corn, while the corn itself drops out at the bottom of the machine. The hopper J is hinged to the front board, N, by the hinges d d, as shown in Fig. 1; and to prevent the corn, when placed in the hopper J, from falling too heavily upon the feeder F, I place above the said feeder the inclined shield S, which is hinged so that it may be raised up for cleaning the pins c or clearing the slots e, in case they should get clogged with the corn.

The machine may be operated by any suitable power applied to the shaft F. If steam or horse power is used, it will be applied to the pulley T, secured on said feeder F. If hand-power is used, a suitable crank will be applied to the feeder F in place of the pulley T.

In use, the corn will be first cut from the cob and then fed into the hopper J. The machine now being put in motion, the pins c c of the feeder F will gradually work the corn through the slots e e in the throat-plate R, whence it will fall upon the apron A among the fingers B, which will catch the silk mingled with the corn and retain it until removed from the fingers by the action of the brush L. In this manner it will be seen that the machine is adapted for very rapid operation, and is practical for its purpose, removing all the silk from the corn, and it is self-cleaning.

Having thus described my invention, what I claim as new, and desire to secure by Letters Patent, is—

1. A corn-silking machine comprising a trav-

eling belt provided with points or fingers, a brush for cleaning the fingers, a hopper, and a feeder, F c, arranged to operate substantially as described.

5. 2. The combination, with the hopper J and the feeder F c, of the slotted plate R and shield S, arranged above the feeder in the hopper J, substantially as and for the purposes set forth.

3. The inclined endless traveling apron A, provided with points B, in combination with hopper J, feeder F c, and slotted plate R, arranged in the hopper, substantially as and for the purposes set forth.

4. In a corn-silking machine, the inclined endless apron A, provided with fingers B, in combination with hopper J, feeder F c, slotted plate R, arranged in the hopper, the shaft M, having pulley K, and the brush L, connected to shaft M, substantially as and for the purpose set forth.

WILLIAM SAMPSON HORN.
